NAILING MACHINE

Arthur A. Cavanaugh, Alameda, Calif.

Application May 9, 1949, Serial No. 92,103

2 Claims. (Cl. 1—46)

1

This invention relates to a nailing machine. In prior nailing machines, difficulties of various kinds have been encountered. Thus, in some machines an excessive number of moving parts are involved. This is unsatisfactory inasmuch as the presence of numerous moving parts inevitably results in wear, mechanical failure or disalignment of the moving parts. When this occurs, it is of course necessary to stop the nailing operation to repair the machine. It may even be necessary to return the machine to a shop for repair by a skilled mechanic.

In some of the prior machines, difficulty has also been encountered owing to the fact that nails become jammed in the delivery chute from the hopper to the nail driving mechanism or, even more seriously, become jammed in the nail driving passage thus causing breakage of parts of the machine.

It is an object of the present invention to provide an improved form of nailing machine.

It is a further object of the invention to provide a nailing machine which involves a minimum number of moving parts.

It is a still further object of the invention to provide a nail driving machine having a minimum number of moving parts and which is capable of dependable, steady delivery of nails from a hopper to the nail driver.

It is a still further and particular object of the invention to provide a nail driving machine which involves a minimum number of moving parts, which is dependable in its operation and which creates little likelihood of jamming of the nail driving passage.

These and other objects of the invention will be apparent from the ensuing description and the appended claims.

This application of a continuation-in-part of my copending application Serial No. 19,911, entitled "Nailing Machine," filed April 9, 1948, and now abandoned.

One form which the invention may assume is exemplified in the following description and is illustrated by way of example in the accompanying drawings, in which:

Fig. 1 is a view showing the nail driving element or mechanism in side elevation and the nail delivery element in vertical section.

Fig. 2 is a top plan view of the machine.

Fig. 3 is a view in vertical section through the nail driving mechanism, showing the nail driver or plunger in its normal, elevated position.

Fig. 4 is a view similar to that of Fig. 3 but showing the nail driver in its lowermost posi-

tion at the lower end of its stroke and in the act of driving and countersinking a nail.

Fig. 5 is a view taken along the line 5—5 of Fig. 1, showing the nail driving mechanism in rear elevation.

Figs. 6 and 7 are sections taken along the lines 6—6 and 7—7, respectively, of Fig. 1 showing details of the nail delivery element.

Figs. 8 and 9 are horizontal sections taken along the lines 8—8 and 9—9, respectively, of Fig. 3 showing details of construction of the nail driving mechanism.

Referring now to the drawings, the nail driving machine is generally designated as 10 and it comprises a nail delivery mechanism or element 11 and a nail driving mechanism or element 12. The nail delivery element 11 comprises a hopper 13 having a T-shaped slot 14 at the bottom thereof and in communication with a U-shaped nail delivery chute 15 having a longitudinal slot 16 formed in the bottom thereof. A guard plate 17 is provided, as illustrated, being hingedly supported at 18 for a purpose explained hereinafter, and as will be seen the lower end 25 of the guard plate 17 lies close to the nail slot 16. A U-shaped shingle nail guard 19 (see Fig. 6) is also provided, which straddles the nail slot 16, and forwardly and downwardly therefrom there is provided a deflector plate 25, the shingle nail guard 19 and deflector plate 25 serving purposes described hereinafter.

The deflector 25 is fixed to a frame bracket 26 by means of screws 27, and caster wheels 28 are mounted on the bracket 26 at the bottom thereof.

A bin 29 also mounted on the bracket 26 is provided and is disposed beneath the nail chute 15 for a purpose explained hereinafter. Brackets or side plates 30 interconnect the nail delivery mechanism 11 and the nail driving mechanism 12 and thus provide a sturdy, rigid structure. A nail chute 31 is fixed at one end to the nail chute 15 in overlapping relationship therewith and, at its other end, is fixed to the nail driving mechanism 12. A longitudinal nail passage or slot 32 is formed in the chute 31. Thus, the nail chute 31 and slot 32 provide a continuation of the nail chute 15 and slot 16. Fixed to and slanting upwardly from the nail driving mechanism 12 is a nail guide or guard member 33. Fixed thereto and extending upwardly and outwardly therefrom and spaced above the nail chute 31, is a nail guard rod 34. The purpose of the guard members 33 and 34 is explained hereinafter.

As thus far described, the machine operates as follows: A supply of finishing nails 35 of the type

employed for nailing hardwood floors is maintained in the supply hopper 13. Agitation of the hopper 13, either manually by shaking it with the hand or automatically owing to vibration of the machine during the nailing operation, will cause nails to fall through the slot 14. Inasmuch as the slot 14 is of T-shape, having a transverse portion and a longitudinal portion, it will be apparent that nails aligned transversely and longitudinally of the hopper will fall therethrough. Any tendency of the nails to pile up and to pass down through the nail chute 15 too rapidly, is prevented by means of the guard plate 17, which opposes sufficient resistance to the nails to prevent an oversupply of nails from falling down the chute. Thus, the guard plate 17, being hingedly supported at 18, will pivot upwardly and to the left as shown by the arrow, so as to allow a steady, even delivery of nails down the chute 15. In the event that a shingle nail or other nail having a larger head than desired should be mixed with the supply of finishing nails, the large head of the nail will not pass through the U-shaped guard 19. The operator, noting that nails are not being delivered below this point, will have his attention drawn to the difficulty and may remove the offending nail manually, thus preventing its passage downwardly into the nail driving mechanism 12.

Naturally, a considerable proportion of nails, instead of falling into the nail chute 15 in alignment with the slot 16 and being delivered in the proper manner, will lie transversely of the nail chute 15 and will not ride in the slot 16. Such nails are effectively removed by means of the deflector plate 25. As illustrated, the plate diverges from the nail slot 16 and will thus deflect nails which are not riding in the slot 16 and will deflect them to one side or the other, causing them to fall into the bin 29.

As the nails pass downwardly through the chute 31 and its nail passage or slot 32, they will exhibit a tendency to jump out of the slot 32 owing to vibration of the machine. Such nails as tend to jump out of the slot 32 will be retained by means of the guard rod 34. When the nails reach the lower end of the chute 31 and approach closely to the nail driving mechanism 12, it also is important that they should be perfectly aligned and that the heads of all the nails should lie in a straight line. To this end, the guard member 33 is provided which, as illustrated, approaches the slot 32 more closely and thus evens up the nails and holds their heads in properly aligned position.

Referring now more particularly to Figs. 3 and 4, the nail driving mechanism 12 comprises an elongated barrel portion 40 which is formed at its upper end with an axial passage 41 of relatively large diameter terminating in a shoulder 42; and nearer its lower end with an axial passage 43 of smaller diameter. A plunger or nail driver 44 is reciprocable within the barrel 40, such driver having a head 45, upper stem or shank portion 46 and a lower shank or stem 47 of smaller diameter and having a sliding fit with a passage 43. The barrel is closed at its upper end by a cap 48 secured thereto by means of screws 49, and a fiber washer 50 is provided for a purpose explained hereinafter. The driver 44 is provided with a collar or limit member 55 fixed to the driver by means of a snap ring 56 and a C-washer 57, as illustrated. An expansion spring 58 is compressed between the C-washer and the shoulder 42, and this spring normally serves to hold the driver in

its elevated position, as illustrated in Figs. 1 and 3.

At its lower end, the barrel 40, which is conveniently tapered as illustrated, is provided with an enlarged recess or passage 59. This recess is a continuation of the passage 43, and it is open at its lower end and is fitted with a cup 60 having a base or bottom flange 61. The cup 60 is yieldably held in place in the passage 59 by means of a snap ring 62 seated in an annular groove 63 formed in the barrel. The cup 60 is formed at its upper end with a conical seat 64 in axial alignment with a nail aligning or nail set passage 65. The nail driver 44 is formed at its lower end with a conical seating portion 70 adapted to seat in the conical seat 64, and with a nail driving member or nail set 71 having a tapered end 71a.

The barrel 40 is also formed with a longitudinal groove or open passage 72 and the cap 48 with a corresponding recess 72a for reception of a lug 73 formed on the collar 55. A knockout plunger 75 is provided, being slidably disposed within the longitudinal groove 72, such knockout plunger being received within an opening 75a formed in the lug 73 and having a head 76 at its upper end and a tapered tip 77 at its lower end. A tension spring 78 is fixed at one end to the head 76 and at its other end to a screw 79 which is fixed to the barrel. The tendency of the tension spring 78, as is apparent, will be to draw the knockout plunger 75 downwardly. However, the expansion spring 58 is a much stronger spring than the tension spring 78 and will normally hold the nail driver 44 in its uppermost position and, therefore, through the medium of the collar 55, lug 73 and head 76 the spring 58 will also hold the knockout plunger 75 in its uppermost position, as illustrated in Fig. 3.

A block 85 is received within a recess 86 formed in the barrel 40 in alignment with the longitudinal groove 72, being fixed to the barrel by means of screws 86a. The block 85 is formed with a passage 87 to receive the knockout plunger 75. Also seated in the recess 86 and at the rear of the block 85 is a stainless steel wearing plate 88, to the rear of which is formed another recess 89 in which is seated a bar magnet 90 having poles 91 and 92.

A nail delivery passage 93 is defined by the stainless steel plate 88 and by a slanting guide plate 94 for the purpose of guiding nails from the lower end of the chute 31 into the passage 59 and thence into the nail set passage 65. It will be seen that the lower end of the chute 31 is spaced a short distance, slightly greater than the diameter of the knockout plunger 75, from the stainless steel plate 88.

The device thus described operates as follows: Nails are delivered to the lower end of the chute 31 in the manner described hereinabove. Referring to Fig. 3, it will be seen that a nail is located in the nail set passage 65 with its head uppermost and its tip lowermost, in readiness to be driven and set into a floor. At this instant, it is important to prevent a second nail from dropping down into the passage 59, as such event would cause jamming of the machine when the nail set 71 descends. This is effectively prevented by means of the bar magnet 90, which has one of its poles 91 disposed above the lower end of the nail chute 31 and its other pole 92 disposed therebelow. It will thus be apparent that the bar magnet 90, which can easily be made sufficiently powerful, will hold the nail firmly in the position shown in Fig. 3, thus preventing it from

falling downwardly and damaging the machine. It also holds the other nails in chute 31.

It is further important, when a nail has been driven and set as illustrated in Fig. 4, that another nail be delivered to the nail set passage 65 at the proper moment. This is effectively accomplished by means of the knockout plunger 75 and the tension spring 78. As mentioned, the tension spring 78 acts to draw the knockout plunger 75 downwardly, but it is a considerably weaker spring than the expansion spring 58. Accordingly, when the head 45 of the nail driver 44 is struck by a hammer, the nail driver will descend very rapidly. However, the only forces acting on the plunger 75 are gravity and the relatively weak tension of spring 78, which will be free to draw the knockout plunger 75 downwardly. The downward travel of the knockout plunger will be much slower than that of the driver 44. Accordingly, by the time the knockout plunger 75 passes downwardly through the passage 87 formed in the block 85 and contacts the head of the nail held by the magnet, the conical seating portion 70 of the driver 44 will be seated in the conical seat 64. Thus, as illustrated in Fig. 4, a nail disengaged from the magnet 90 and knocked downwardly by the knockout plunger 75, will merely fall through the nail passage 93 into the passage 59 and will rest in the position illustrated without in any way causing jamming of or damage to the machine. When the driver returns to its rest position, the nail shown in passage 59 in Fig. 4 will drop into the nail set passage 65. Also, the knockout plunger 75 will return to its rest position, thus clearing the end of the chute 31 to allow another nail to drop from the chute and be held in position by the magnet 90.

If the event that a nail of considerably greater length than average is delivered to the machine, it will be automatically ejected by means of the deflector plate 94. Thus, referring to Fig. 3, it will be evident that, as each nail descends toward the bottom of the nail chute 31, its head will be held firmly in contact with the chute by means of the guard member 33. Thus the lower end of a long nail will contact the upper end of the deflector plate 94 and will be held away from the nail passage 93. When the knockout plunger 75 descends, it will strike the head of the long nail and will thus eject it from the machine. The machine, of course, will miss a nail but such is not of substantial importance as compared with jamming of the machine and/or damage to the nail set which might result from delivery of a long nail to the nail set passage 65.

A further important operating feature of the machine is that, when the driver 44 descends under the blow of a hammer, it limits at the bottom by engagement of its conical seating portion 70 with the conical seat 64. Thus vibration is reduced, likelihood of damage to the machine is lessened and accuracy is increased. On the up-stroke of the driver, it limits against the fiber washer 50, which also reduces vibration, etc.

It will thus be apparent that a nail driving machine has been provided which satisfies the objects set forth hereinabove. Thus, the machine involves a minimum of moving parts, the only moving parts being the nail driver 44 and the knockout plunger 75. Various means are provided to insure proper delivery of nails to the nail driving mechanism, such, for example, as the guard plate 19 and the deflector plate 25; also the guard members 33 and 34. Magnetic means is provided

and is so located as to hold one nail at the bottom of and free of the nail delivery chute in proper position for delivery to the nail set passage, while another nail is located in the nail set passage to be driven into a floor. Means is provided in the form of the knockout plunger 75 and tension spring 78 to insure the delivery of a nail each time that one is needed and at the proper instant to avoid jamming of the machine. As noted, the nail driver 44 limits at the bottom rather than at the top, which is desirable for the reasons stated. Also, inasmuch as the cup 60 is a removable wearing element, and a plentiful supply of the same may be kept on hand, wear thereof is of relatively minor importance. Still other advantageous features have been noted above; for example, the provision of means for ejecting nails too great in length and the provision of a wearing plate adjacent the magnet.

While I have shown the preferred form of my invention, it is to be understood that various changes may be made in its construction by those skilled in the art without departing from the spirit of the invention as defined in the appended claims.

Having thus described my invention, what I claim and desire to secure by Letters Patent is:

1. A nail driving machine comprising a barrel having an axial passage formed therethrough, a nail driver mounted for reciprocation in said passage, nail set means including a nail set passage at the lower end of said barrel, said nail set passage being in axial alignment with said driver, a spring normally elevating said driver and holding it away from said nail set passage, a chute for feeding nails by gravity to said nail set passage, the lower end of said chute being in communication with said nail set passage, magnetic means operable to hold the lowermost nail in said nail chute away from said nail set passage, knockout means including a spring for operating the same, said spring being substantially weaker than the spring for elevating said driver, said knockout means being operable to detach a nail from said magnetic means for delivery thereof to said nail set passage, means interconnecting said driver and knockout means normally operable to inactivate the latter and to hold the same out of contact with said lowermost nail, said interconnecting means being operable to cause operation of said knockout means in timed relation to reciprocation of said plunger.

2. A nail driving machine comprising a barrel having an axial passage therethrough, a nail driver mounted for reciprocation within said passage, removable nail set means seated in the lower end of said passage, said nail set means including a nail set passage in axial alignment with said driver, an expansion spring normally operable to elevate said driver and hold the same away from said nail set passage, a chute for feeding nails by gravity to said nail set passage, the lower end of said chute being in communication with said nail set passage, magnetic means disposed adjacent to the lower end of said chute operable to hold the lowermost nail therein away from said nail set passage, a nail knockout plunger in alignment with said lowermost nail and operable to detach the same from said magnet for delivery thereof to said nail set passage, a tension spring for operating said knockout plunger, and means interconnecting said nail driver and knockout plunger normally operable to elevate said plunger and hold the same away from said lowermost nail but releasing the same when said nail driver is

driven downwardly into said nail set passage, said tension spring being a relatively weak spring such as to cause travel of said knockout plunger at a relatively slow speed compared to the travel of said nail driver under the impact of a hammer blow.
